UNITED STATES PATENT OFFICE.

GEORGE PARK SALLE AND GEORGE F. SALLE, OF BOISE, IDAHO.

FOLDING CAMP-BED.

1,359,844.

Specification of Letters Patent. Patented Nov. 23, 1920.

Application filed January 8, 1920. Serial No. 350,136.

To all whom it may concern:

Be it known that we, GEORGE P. SALLE and GEORGE F. SALLE, citizens of the United States, residing at Boise, in the county of Ada and State of Idaho, have invented certain new and useful Improvements in Folding Camp-Beds, of which the following is a specification.

Our invention relates to new and useful improvements in beds and more particularly to a folding camp bed.

The principal object of the invention is the provision of a camp bed which may be folded so that it may be readily carried upon an automobile when touring.

Another object of the invention is the provision of a bed having a canvas strip for supporting the person, said strip being yieldably connected to the bed frame.

A still further object of the invention consists in the construction of the frame work of the bed of metal so that it will be sanitary.

With these and other objects in view my invention consists of the novel details of construction and arrangement of parts which will be more clearly understood from the following specification and drawings in which:—

Figure 1 is a side elevation.

Fig. 2 is an end view.

Fig. 3 is a fragmentary corner of the end opposite to that shown in Fig. 2 and,

Fig. 4 is a top plan.

In carrying out our invention we provide a metal frame which may be folded into compact form and said frame is adapted to have a canvas strip, or strip of other suitable material, yieldably suspended there-

from. The frame comprises the angle iron side strips 1 having the angle iron side strips 2 pivotally connected to the outer face thereof and the angle iron side strips 3 pivotally connected to the inner face, at a point

spaced from the end. As shown when in extended position the angle iron strips 1 and 3 form a substantially continuous strip extending at an angle as more clearly illustrated in Fig. 1 of the drawings. The angle iron side strips 2 extend at an angle upwardly from the end of the strips 1 as shown and for a purpose to be later described. Angle iron legs 4 are pivotally connected to each side strip 1 at 5 and these legs are

adapted to fold longitudinally of the strips 1. Braces 6 are pivotally connected to the

strips 1 at 7 and are provided in their opposite ends with openings adapted to fit over threaded bolts which receive the thumb nuts 8. An angle iron end strip 9 secures the two side strips 1 together and the angle iron end strip 9 is secured to the side strips 1 by means of threaded bolts which pass therethrough and receive the thumb nut 10 as more particularly illustrated in Fig. 4 of 65 the drawings. Brace strips 11 are pivotally connected to the end strips 9 at 12 and are provided in their opposite ends with openings through which a bolt secured to the legs 4 extends. A thumb nut 13 is 70 adapted to be received on the threaded bolt as more particularly set forth in Fig. 3 of the drawings.

The angle iron end strip 14 connects the outer ends of the side angle iron strips 2 75 and is secured to said side strips 2 by means of bolts and thumb nuts 15. Legs 16 of angle iron are pivotally connected to the side strips 3 at 17 and these legs 16 are provided adjacent their opposite ends with 80 openings through which bolts 18, connected to the angle iron end strip 14, pass and these bolts receive the thumb nuts 19 as clearly shown in Figs. 1 and 2 of the drawings. The legs 16 are adapted to swing 85 upon the pivot point 17 and extend longitudinally of the side strips 3 when in folded position. Brace strips 20 are pivotally connected to the end angle iron strip 14 at 21 and are provided in their opposite ends with 90 openings through which threaded bolts connected to the legs 16 are adapted to pass. Thumb nuts 22 are adapted to be received on the threaded bolts to secure the brace to the leg. 95

Coiled springs 23 are secured to each of the end strips 9 and 14 and these coiled springs are adapted to yieldably support a canvas strip 24. While we have described the strip 24 of canvas it will be understood 100 that it might equally as well be made of other material. As shown more particularly in Fig. 4 of the drawings the canvas strip 24 is provided with a plurality of loops or eyes 25 which receive the rings 26 which in turn receive the hooked ends of the springs 23. The angle iron end strips 9 and 14 are provided with a plurality of transversely spaced perforations 27 which receive the opposite hooked ends of the 110 springs 23.

Having fully described the detailed con-

struction of our invention it is thought that the advantages and manner of using will be clearly understood. As stated in the objects of our invention we propose to construct a folding camp bed which may be carried upon an automobile when touring. It is a well known fact that when touring it is often impossible to reach a town or city where hotel accommodations may be secured. At the same time some persons, when touring, desire to sleep in the open air. It is to accommodate such persons that our invention is intended and it is not necessary, when touring to reach a city or town where hotel accommodations may be found. In the drawings we have illustrated the several parts of the invention in position when the camp bed is extended and ready for use. As is shown the canvas strip 24 is yieldably supported by the springs 23 and therefore form a comfortable yieldable support for the person. At the same time the side strips 1, 2, and 3 are so positioned and inclined as to hold the bed in extended position and there is no chance of the bed collapsing with the person. The side strips are also pivotally connected together in such a manner that the legs which are connected thereto may be readily folded in such a position as to take up little space when the side strips themselves are folded. When it is desired to fold the bed the thumb nuts 18 will be removed and the legs 16 will be folded upon the pivot 17 to lie longitudinally of the side piece 3. The thumb nuts 8 and 13 will also be removed and the braces 6 and 11 may swing upon their pivots 7 and 12 respectively. The legs are then swung upon the pivots 5 to extend longitudinally of the side piece 1. The side strip 3 is then swung upon the pivot by which it is connected to the strip 1 and the side strip 2 will also be swung upon its pivot so that the strips 3 and 2 will lie longitudinally or parallel with the strip 1. When folded in this position the canvas strip 24 will also be folded and the coiled springs 23 will be released from tension. It will thus be seen that the bed may be folded in compact form so that it may be easily carried upon an automobile. When the frame is extended in position for use it will be noted that the coiled springs 23 are placed under tension so as to hold the canvas strip 24 under tension to properly support the person.

The foregoing description and the accom-

panying drawings have reference to what might be considered the approved, or preferred, form of our invention. We desire it to be understood that we may make such changes in construction, combination and arrangement of parts, materials, dimensions, etc., as may prove expedient and fall within the scope of the appended claims.

Having fully described our invention what we claim as new and desire to secure by Letters Patent is:—

1. In a device of the class described the combination of a collapsible frame comprising end strips, a pair of side strips connected to each end strip, means pivotally connecting the lower ends of the side strips, a pair of legs for supporting each end strip, a pair of extension side strips pivotally connected to one pair of the side strips intermediate their ends and to the lower end of the opposite legs, bracing means disposed between the last mentioned side strips and the adjacent legs, bracing means disposed between the end strips and the adjacent legs, and a flexible strip yieldably supported upon the collapsible frame.

2. A folding camp bed comprising a collapsible frame and a flexible strip yieldably supported therein, said frame comprising end strips, a pair of side strips connected to each end strip, means pivotally connecting the lower ends of the side strips, legs pivotally connected to the frame, a pair of extension side strips pivotally connected to one pair of side strips intermediate the ends and to the lower ends of the opposite legs.

3. In a device of the class described, the combination of a collapsible frame and a flexible strip yieldably supported therein, said frame comprising end strips, a pair of side strips connected to each end strip, means pivotally connecting the ends of the side strips, legs for supporting the frame, a pair of extension side strips pivotally connected to one pair of the side strips intermediate their ends and to the lower end of the opposite legs, and bracing means disposed between the last mentioned side strips and the adjacent legs.

In testimony whereof we affix our signatures in presence of two witnesses.

GEORGE PARK SALLE.
